UNITED STATES PATENT OFFICE.

ANDREW J. HABERMACHER, OF FORT WORTH, TEXAS.

FIRE BOX.

Application filed March 3, 1922. Serial No. 540,906.

To all whom it may concern:

Be it known that I, ANDREW J. HABERMACHER, a citizen of the United States, residing at Fort Worth, in the county of Tarrant and State of Texas, have invented a new and useful Fire Box, of which the following is a specification.

This invention relates to fire-boxes for boiler furnaces designed for use in connection with locomotive, stationary and marine boilers and in any other structures where oil is used as a fuel.

It is the practice in oil burning furnaces to provide air holes for directing fresh air into the fire-boxes but these have been objectionable because the currents of air have tended to intercept the fire and prevent it from reaching the splash wall. Consequently imperfect combustion has resulted and there has been a considerable waste of fuel through the discharge of unconsumed portions producing a heavy smoke.

It is an object of the present invention to provide simple and efficient means for preventing the inflowing air from intercepting the fire blast, but which, nevertheless, permits thorough mixing of the air with the fuel and promotes combustion, thereby saving fuel and rendering the combustion products substantially smokeless.

With the foregoing and other objects in view which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings the preferred form of the invention has been shown.

In said drawings—

Figure 1 is a plan view of a portion of a fire-box showing a bridge therein such as constitutes the present invention.

Figure 2 is a transverse section on line 2—2, Figure 1.

Referring to the figures by characters of reference 1 designates a fire-box of any preferred construction adapted for burning fuel oil. 2 designates the burner nozzle for di-

recting the fire blast into the furnace, and 3 designates the splash wall against which the fire blast is directed. There is provided in the bottom of the fire-box a relatively wide air intake port 4 and the fire blast is directed over the central portion of this port. Ordinarily the inrushing air tends to dissipate the fire at this point with the result that it does not properly come against the splash wall. To overcome this objectionable action a bridge 5 is placed across the middle portion of the port directly under the line of the fire blast and, consequently, the air will not ascend directly under the fire blast but will be divided into two currents entering the fire-box at opposite sides of the blast. Thus the impact of the blast against the splash wall will not be interfered with but nevertheless a sufficient amount of air will be admitted to the fire-box and be mixed with the fuel to insure practically perfect combustion and a substantially smokeless product of combustion. As the air will not deflect the fire blast upwardly the fire will hit the splash wall close to the bottom thereof and will mix with the air between the air port and the splash wall so as to insure proper combustion.

What is claimed is:—

1. In an oil burning furnace having a splash wall at one end, means spaced from the splash wall for directing a fire blast against the splash wall, and an air intake port in the bottom of the furnace, of a bridge extending over the port below the line of the fire blast.

2. In an oil burning furnace having a splash wall at one end, means at the other end for directing a fire blast against the splash wall, and an air intake port in the bottom of the furnace, of means between the air port and the line of the fire blast for preventing dissipation of the fire blast by the inflowing air.

In testimony that I claim the foregoing as my own, I have hereto affixed my signature in the presence of two witnesses.

ANDREW J. HABERMACHER.
